REUSEABLE PLUG FUSE

Otto C. Larson, Sr., Brooklyn, N. Y.

Application May 17, 1951, Serial No. 226,786

5 Claims. (Cl. 200—130)

1

This invention relates to fuses and, particularly, to the more or less conventional screw-in type of fuse. More particularly, the invention deals with fuses of the kind under consideration having means, whereby parts of the fuse may be removed and the burned out fuse element replaced, so as to provide indefinite use of the main body portion of the fuse.

The novel features of the invention will be best understood from the following description, when taken together with the accompanying drawing, in which certain embodiments of the invention are disclosed and, in which, the separate parts are designated by suitable reference characters in each of the views and, in which:

Fig. 1 is a cross-sectional view through a more or less standard type of fuse, showing one method of separating the fuse body parts and novel mounting of a fuse element for replacement or removal thereof.

Fig. 2 is a view, similar to Fig. 1, showing another method of coupling and uncoupling the body parts.

Fig. 3 is a plan view of another form of plug which I employ.

Fig. 4 is a partial section on the line 4—4 of Fig. 3; and

Fig. 5 is a view similar to Fig. 4 showing another form of construction.

With fuses of the type and kind under consideration, it has been customary to employ a fused plug body with a positive and fixed arrangement of fuse element therein so that, when the fuse has blown, the entire fuse was disposed of. It is the purpose of my invention to modify and construct devices of the kind under consideration in such manner that the fuse element itself, when burned out or blown, can be replaced simply by another element at an extremely nominal cost, thus extending to the body structure of the fuse, as a whole, a long, useful life.

In Fig. 1 of the drawing, I have shown what may be termed a standard or conventional type of fuse body, comprising a hollow plastic or other insulation base 10 having a downwardly extending conical terminal end 11, with a center terminal 12 exposed at the outer surface thereof. The body 10 has an outwardly projecting annular flange 13. At 14 is shown a thimble-shaped cap, usually composed of glass, the peripheral walls of the cap 14 being threaded, as indicated at 15, to receive the threaded metallic shell 16, having an inturned, lower end 17, which seats upon the flange and which draws the cap 14 firmly onto the body 10.

2

One wall of the cap 14 has a longitudinal groove or keyway 18 therein and slidably mounted in this groove or keyway is a removable key bar 19 which I employ for detachably coupling the parts for removal of a fuse element 20, mounted as later described. The key bar 19 has an outer grooved surface 21, which is adapted to be frictionally placed beneath the threaded portion of the sleeve 16 to hold the key bar in position and, at the same time, facilitate normal use of the plug in threading the same into and out of a fuse socket.

Arranged within the chamber 22 of the body 10 is a terminal strip 23, soldered or otherwise to the terminal 12 and the upper end of the terminal strip 23 has a spring end 24, in which one end portion 20' of the fuse element 20 is frictionally and tensionally supported. Another contact strip 25 is disposed on the body 10 and includes a portion 26 wrapped around the flange 13 to establish contact with the sleeve 16, as clearly illustrated in the drawing. The contact strip 25 is fixed to the body 10 by a rivet, or the like, 27 and the other end 20" of the fuse element 20 is adapted to be placed between the upper free end 28 of the contact strip 25 and the body 10 and having a positive frictional engagement with the end 28. From the foregoing construction, it will be apparent that, as and when the fuse element blows or burns out, this element can be replaced by a new fuse element by simply drawing upwardly on the key bar 19, removing it from the recess 18, whereupon, the cap 14 can be turned out of the sleeve 16, the old fuse element removed and a new one placed in position, after which, the cap 14 is replaced and the key bar 19 again put into operative position.

In Fig. 2 of the drawing, I have shown a slight modification of the construction shown in Fig. 1, wherein a more or less standard fuse body is modified to a slight extent in detachably coupling the body parts and in establishing electrical circuit between parts of the fuse. In this figure, 29 represents a body substantially similar to the body 10 and 30 represents a cap, substantially similar to the cap 14. However, in this construction, the threaded shell 31, in addition to having a threaded engagement with the cap 30, is also positively fixed to the cap by a soldering anchorage, as is generally known in the art.

In Fig. 2, a strip 32, similar to the strip 23, is employed for completing circuit to the terminal end 33, similar to the terminal end 12. The strip 32 is bent over the upper portion of the body 29, as seen at 34, and within the chamber of the body, the strip 32 has a spring contact strip 35 fixed

thereto for engagement with one end of a fuse element 36, generally similar to the element 28.

The body 29, on a wall thereof opposed to the strip 32, has another strip 37 enveloping the upper end portion thereof and this strip, together with a spring catch and contact device 38, are fixed to the body 29 by a rivet, or otherwise, as at 39. The upper end of the catch and contact 38 has an end 40, similar to the end 28 for engagement with the other end of the fuse element 36. The lower end portion of the catch and contact 38 has an offset catch element 41 adapted to engage the inturned lower portion 42 of the shell 31, the catch 38 operating in a slot in this inturned portion and is shown in the locked position in Fig. 2. By pressing inwardly on the lower fingerpiece end 43 of the catch 38, the body 29 will be released for displacement from the cap 30 and shell 31.

It will also appear that the fingerpiece end 43 of the catch and contact 38 operates in a recess 44 in the flange portion of the body 29 and protrudes sufficiently beyond this flange portion to be engaged by a tool or the fingernail of a hand. The catch 38 also establishes the electrical connection of one end of the fuse element 36 with the shell, as will be apparent. However, the catch 38 will not interfere with the rotation of the fuse in screwing the same into and out of a fuse socket.

In Figs. 3 and 4 of the drawing, I have shown a novel type of plug fuse, wherein a unitary plug body assemblage 45 is employed, comprising a solid core 46 of insulating material and an outer sleeve 47 of similar material, the sleeve having, on its upper surface, projecting segments 48, having undercut grooves 49 on opposed parallel edges for reception of a transparent slide or strip 49 which, in the construction shown, is illustrated as a flat strip, but this member can be of any desired cross-sectional form. The strip 49 has a frictional engagement with the body 47 and is contained within boundaries of the body, as seen in Fig. 3, but can be forcibly removed whenever desired.

Actually, the body 45 is in the form of a screw-in socket, with which conventional plugs are coupled for completing circuits to electrical appliances and this body has been modified to convert the same to a fuse by simply interposing a fuse element 50 between the spring contact portions 51 and 52 in the manner clearly seen in Fig. 4 of the drawing. Normally, these contact portions would receive the spaced terminals of the conventional plug. As indicated in Fig. 2, the spring contact portion 51 is in circuit with the threaded shell 54 of said body. It will thus be apparent that, by the slight conversion or modification in the structure of the body, the same is converted into a practical fuse, wherein the fuse element 50 can be replaced, when blown, by simply removing the slide or strip 49, substituting the new fuse element and then replacing the slide 49 for a continued use of the fuse.

In Fig. 5 of the drawing, I have shown another form of construction, wherein a more or less standard type of socket 45' is shown, that is to say, a socket generally similar to the socket 45, such as are employed in connection with plugs having spaced terminals to complete electrical circuit with spring contacts 51' and 52' of the socket body 45'. In Fig. 5, a fuse element 50', similar to the fuse 50, is bridged across the terminals or spring contacts 51', 52' and these contacts are held in firm engagement with the ends

of the fuse element by the spaced posts or bars 55, 56 of the plug-like body 57. The body 57 is modified to the extent that the outer end of the bore 58 thereof has a recess 59 in which a suitable transparency 60 is fixed, this transparency giving visibility to the fuse element 50'. With the device, as shown in Fig. 5, it will be understood that, when the fuse element 50' blows or burns out, the socket body 45' is removed from the fuse socket, after which the plug-like body 57 is pulled out of the body 45', whereupon the burned out fuse element can be removed and a new fuse element 50' placed in position, after which the body 57 is replaced and inward movement of the bars 55, 56 will securely and firmly establish engagement of the contacts 51', 52' with the ends of the fuse element 50'.

It will be apparent that, with the several forms of construction shown, the fuse elements comprise a fuse strip having, at the center portion thereof, the desired control, from a standpoint of amperage from the lowest to the highest amperage usually provided in plugs of this type and kind and otherwise these fuse elements have the inturned contact ends for establishing engagement with the different contacts disclosed. The body portion of the fuse plugs can be suitably marked to designate the amperage of the fuse and, with structures of the kind under consideration, in the sale of one fuse body, a number of fuse elements can be sold with the body for replacement or removal whenever desired and, to avoid confusion in this regard, each fuse element can be stamped to identify amperage thereof. This will be beneficial in the individual sale of the elements for replacement of old and burned out elements.

In considering Fig. 1 of the drawing, it will be apparent that part of the threaded portion of the shell 16 is cut-out to receive the key bar 19, which keys the shell against rotation. It will also appear that the fuse element has a central amperage control portion and short substantially parallel terminal ends.

Having fully described my invention, what I claim as new and desire to secure by Letters Patent is:

1. A fuse of the class described, comprising two detachably coupled body parts of insulating material arranged one upon the other, one of said parts having a terminal at the outer end thereof, a threaded sleeve forming the other terminal, said sleeve being in engagement with the other of said parts and engaging the first part to form an assemblage of said parts, spaced spring contacts within said parts, one contact being in circuit with said end terminal, the other contact being in circuit with said sleeve terminal, a fuse element detachable with and bridging and electrically connecting said spring contacts, and means movable on and keyed to one of said parts to render the fuse element accessible for replacement.

2. A fuse of the class described, comprising two detachably coupled body parts of insulating material arranged one upon the other, one of said parts having a terminal at the outer end thereof, a threaded sleeve forming the other terminal, said sleeve being in engagement with the other of said parts and engaging the first part to form an assemblage of said parts, spaced spring contacts within said parts, one contact being in circuit with said end terminal, the other contact being in circuit with said sleeve terminal, a fuse element detachable with and bridging and elec-

trically connecting said spring contacts, means movable on and keyed to one of said parts to render the fuse element accessible for replacement, and said means comprising a bar keyed to and slideable on the second named part and engaging said sleeve to retain the sleeve against rotation on said body part.

3. A fuse of the class described, comprising two detachably coupled body parts of insulating material arranged one upon the other, one of said parts having a terminal at the outer end thereof, a threaded sleeve forming the other terminal, said sleeve being in engagement with the other of said parts and engaging the first part to form an assemblage of said parts, spaced spring contacts within said parts, one contact being in circuit with said end terminal, the other contact being in circuit with said sleeve terminal, a fuse element detachable with and bridging and electrically connecting said spring contacts, means movable on and keyed to one of said parts to render the fuse element accessible for replacement, and said means comprising a spring catch and contact exposed through both of said body parts and engaging said sleeve to establish electric circuit with the sleeve and to retain the body parts against relative movement.

4. A fuse device of the class described, comprising a body of insulating material, said device having a terminal at one end and an external threaded sleeve forming the other terminal, spaced spring contacts within said body, one contact being in circuit with said terminal end, the other contact being in circuit with said sleeve

25

terminal, a fuse element detachable with and bridging said contacts to complete an electric circuit therebetween, means retaining the fuse element in contact with said terminals, and means comprising a member movable relatively to and keyed to the body part for rendering the fuse element accessible for replacement.

5. A fuse device of the class described, comprising a body of insulating material, said device having a terminal at one end and an external threaded sleeve forming the other terminal, spaced spring contacts within said body, one contact being in circuit with said terminal end, the other contact being in circuit with said sleeve terminal, a fuse element detachable with and bridging said contacts to complete an electric circuit therebetween, means retaining the fuse element in contact with said terminals, means comprising a member movable relatively to and keyed to the body part for rendering the fuse element accessible for replacement, and said member comprising a bar keyed to said threaded sleeve to prevent rotation of the sleeve on said body part.
